DESIGN FOR A DRESS

Bernard Hurwitz, New York, N. Y.

Application January 27, 1941, Serial No. 98,452

Term of patent 3½ years

To all whom it may concern:

Be it known that I, Bernard Hurwitz, a citizen of the United States of America, residing in New York, county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific beaded trimming around the cuffs and the neck in association with the pin tucks extending fan-wise below the front neckband and the stitched tucks at the waistline, all as shown.

I claim:

The ornamental design for a dress, as shown and described.

BERNARD HURWITZ.
